UNITED STATES PATENT OFFICE.

GEORGE W. SWEENEY, OF NEW YORK, N. Y., ASSIGNOR TO JAMES AUGUSTUS HAMILTON, FOR HIMSELF AND AS TRUSTEE, OF SAME PLACE.

CAR-AXLE BOX.

SPECIFICATION forming part of Letters Patent No. 279,506, dated June 12, 1882.

Application filed April 7, 1883. (No model.)

To all whom it may concern:

Be it known that I, GEORGE W. SWEENEY, a citizen of the United States, residing at New York, in the county and State of New York, have invented new and useful Improvements 5 in Car-Axle Boxes, of which the following is a specification.

This invention relates to the construction of dust-shields for car-axle boxes; also, to the arrangement of springs for resisting the longitudinal thrust of the axle, and to the construction and arrangement of oil-receptacles for lubricating the journals, as hereinafter fully described, and illustrated in the accompanying drawings, in which—

Figure 1 is a vertical longitudinal section, showing the parts in position within the box. Fig. 2 is a vertical cross-section on the line $z-z$, Fig. 1. Fig. 3 shows the dust-shield detached, partly in side view and partly in section. Fig. 4 is a vertical section thereof. Figs. 5 and 6 illustrate a modification.

Similar letters indicate corresponding parts. The letter A designates the body of an axle-box, and B the journal of a car-axle, entering the box through the usual opening, C, in the rear end thereof. Said opening C is closed, to prevent the entrance of dust, &c., to the axle-box, by a shield, D, which slides into a recess, 25 E, at the rear end of the box, and surrounds the body of the axle at that place, the shield being put in place prior to the introduction of the axle. This dust-shield is composed of a diaphragm, F, of cloth or other flexible material, and of a rigid frame, G, supporting the diaphragm, the latter being attached to the frame in such a manner that it is expansible, and thus adapts itself to the motions of the axle-box.

In the diaphragm F is an opening, H, to receive the journal, and at a distance from the edge of this opening the diaphragm is provided with a rigid ring, I, so that such edge takes the form of a flange, u, projecting inward from the ring. Said flange u thus is the part of the diaphragm which is in contact with the axle, and, due to its flexible nature, the flange readily adjusts itself to the diameter of the axle, thus always preserving a tight joint therewith. The material composing the dia-

phragm is doubled, and the ring I is attached thereto between its two layers by lines of stitching, t, on opposite sides of the ring, whereby the ring is securely held in place, and, moreover, is concealed or protected.

On the ring I is an inwardly-projecting flange, J, of felt or other similar material, which is formed by bending a strip of the desired material upon itself around the ring, and which is substantially flush with the edge of 6 journal-opening H, it being interposed, like the ring, between the layers of the diaphragm, so that by this flange said edge of the journal-opening is re-enforced, and obtains a superior body or fullness, tending to improve its effect. 6

The frame G of the diaphragm is divided centrally and in a vertical plane into two parts or sections, G' G'', which are connected together by telescopic tubes K, one at the top and one at the bottom of the frame, so that the 7 frame-sections are movable toward and away from each other, and permit the adjustment of the frame in width to the recess E of the axle-box. In order to render said frame G self-adjusting, a spring, N, is interposed between the 7 ends of the frame-sections in both tubes K, this spring thus acting on both sections with a tendency to force the same away from each other.

For the purpose of resisting the longitudinal 8 thrust of the car-axle in the motions of the axle-box, I use, in lieu of the usual end flange, a spring, O, which is arranged in the box in the proper manner to act on the end of the axle-journal. Said spring O bears on a 8 washer, P, which in turn bears on the journal at the proper point, and, to support as well as protect the spring, it is inclosed in a casing, Q, which is attached to the cap Q' of the journal, it being in this example made in one piece 9 therewith. This casing Q is open at the inner end, where it faces the journal, and is provided at that place with a recess, s, adapted to receive the washer P, it being closed at the outer end. In the center of the spring O, which is 9 in this example a spiral, is situated a screw-bolt, R, the head of which is sunken into the face of the washer P, and which extends through the closed end of the casing Q at the free end, where it is provided with a nut, R', so that by 1

properly adjusting this nut the tension of the spring can be increased or diminished. When it is desired to remove the spring and its concomitants from the axle-box, the nut R' is tightened to draw the washer into the recesses and out of contact with the journal, while, when the parts have been replaced in the box, the nut is loosened to allow the washer to resume a normal position, as shown in Fig. 1, and in any motions of the box which may then take place the washer plays in and outward in the recess.

If desired, the spring O may be duplicated, as shown in Fig. 6, and in that case the washer P is common to both springs.

The bottom A' of the axle-box is detachable, and supports an oil-receptacle, S, fitting into the box, such receptacle and the detachable bottom being integral or in one piece. In the top of the oil-receptacle S are a series of holes, into which are fitted tubes T, the latter resting in said top by means of flanges on their upper ends, and containing wicks U for conveying the oil from the oil-receptacle to the journal.

Said wicks U are sustained in a working position by means of spiral springs U', one to each wick, which surround the wicks and rest on flanges T', projecting inwardly on the lower ends of the wick-tubes. By the arrangement of the wick-springs U' on the flanges T', the wicks are left free below the lower ends of the wick-tubes, which latter terminate above the bottom of the oil-receptacle, and the proper absorption of the oil by the wicks is insured.

For the purpose of securing the detachable bottom A' of the axle-box, I make use of screw-bolts V, which extend through spiral springs W, arranged in vertical passages X in the side walls of the box, and which rest on the springs by means of their heads V', while they extend through said bottom at the free ends, where they are provided with nuts V''. These nuts V'' are fitted to recesses Y, which are formed on the bottom of the box, in this example, by parallel ribs cast to said bottom, and when it is desired to tighten the nuts the bolts V are drawn downward against the action of the springs W to bring the nuts out of the recesses, while if, when the nuts have been set, the bolts are released, the nuts re-enter the recesses and are firmly held therein by the action of the springs, so that they are not liable to work loose.

In some cases the spring-casing Q may be omitted and the spring O arranged between the end of the journal and the front side of the box, with or without a support, and in that event a wedge, O', Fig. 5, may be arranged between the spring and said side of the box, for regulating the tension of the spring.

What I claim as new, and desire to secure by Letters Patent, is—

1. A dust-shield for a car-axle box, composed of the supporting-frame G, provided with a flexible diaphragm, F, having an opening to receive the journal of the axle, in combination

with the rigid ring I, secured to the diaphragm at a distance from the opening to leave an inward-projecting flexible flange, which flange is capable of conforming itself to axles of varying size, substantially as described. 70

2. A dust-shield for car-axle boxes, composed of the supporting-frame G, provided with the flexible diaphragm F, having an opening, and composed of two thicknesses, in combination with the rigid ring I, secured between the two thicknesses at a distance from the opening to leave an inward-projecting double flange, u, substantially as described. 75

3. A dust-shield for car-axle boxes, composed of the supporting-frame G, provided with the flexible diaphragm F, having an opening; and composed of two thicknesses, in combination with the rigid ring I, secured between the two thicknesses at a distance from the opening to leave an inward-projecting flexible flange, u, and the flange J, of felt or equivalent material, secured to the rigid ring between the two thicknesses of the diaphragm, and flush with the edge of the opening in the 85 same, substantially as described.

4. A dust-shield for car-axle boxes, composed of the supporting-frame G, provided with the flexible diaphragm F, composed of two thicknesses, and provided with an opening to receive the axle and journal, in combination with the rigid ring I, secured between the two thicknesses of the diaphragm by two annular lines of stitches, and located at a distance from the journal-opening to form an inward-projecting flexible flange, u, substantially as described. 95

5. The combination, with the flexible and expandable diaphragm having a journal-opening, of the diaphragm-supporting frame divided vertically into two sections which are connected together by telescopic tubes, to render the frame adjustable in width, substantially as described. 105

6. The combination, with the flexible and expandable diaphragm having a journal-opening, of the diaphragm-supporting frame divided vertically into two sections, the telescopic tubes connecting the frame-sections with each other, and the spiral springs arranged in said 110 tubes to act on both frame-sections, substantially as and for the purpose described. 115

7. The combination, with an axle-box and the journal of the car-axle, of the journal-cap Q', provided with an attached case, Q, within the axle-box, and the coiled spring located in the case to act on the end of the journal, substantially as described. 120

8. The combination, with an axle-box and the journal of a car-axle, of the journal-cap Q', provided with a case, Q, within the axle-box, an independent washer, P, arranged to bear against the end of the journal, and the coiled spring O, located within the case, and having one end bearing on the washer and the other 125 against the case, substantially as described. 130

9. The combination, with a car-axle box and

car-axle journal, of the washer bearing on the end of the axle, the spring bearing on the washer, the spring-casing attached to the cap of the journal and provided at its open end 5 with a recess to receive the washer, and the screw-bolt having its head sunken into the face of the washer and extending through the closed end of the spring-casing, where it is provided with a nut, substantially as and for the purpose described.

10. The combination of the axle-box and the detachable oil-receptacle, having its top wall provided with perforations, with the wick-tubes T, arranged in said perforations, and 15 having lateral flanges at their upper ends, which rest on the top wall of the oil-receptacle, substantially as described.

11. The combination of the axle-box and the detachable oil-receptacle, having its top wall 20 perforated, with the wick-tubes T, supported at their upper ends in said perforations, and

having at their lower ends the inwardly-projecting flanges T', and the coiled springs having their lower ends supported by said flanges, substantially as described.

12. The combination, with a car-axle box having its side walls provided with vertical passages, of the detachable bottom to such box, the spiral springs arranged in said passages, and the screw-bolts extending downward 25 through said springs, with their heads resting thereon and through the bottom of the box, where they are provided with nuts which are fitted to recesses on the box-bottom, substantially as and for the purpose described.

In testimony whereof I have hereunto set my hand and seal in the presence of two subscribing witnesses.
